UNITED STATES PATENT OFFICE.

JOHN G. GROSHEIM AND GEORGE L. SEAMAN, OF CINCINNATI, OHIO.

SWITCHING APPARATUS FOR STREET-CARS.

SPECIFICATION forming part of Letters Patent No. 611,449, dated September 27, 1898.

Application filed April 27, 1898. Serial No. 679,025. (No model.)

To all whom it may concern:

Be it known that we, JOHN G. GROSHEIM and GEORGE L. SEAMAN, citizens of the United States, residing at Cincinnati, in the county of Hamilton and State of Ohio, have invented 5 certain new and useful Improvements in Switching Apparatus for Street-Cars; and we do declare the following to be a full, clear, and exact description of the invention, such as 10 will enable others skilled in the art to which it appertains to make and use the same, reference being had to the accompanying drawings, and to the figures of reference marked thereon, which form a part of this specification. 15

This invention relates to certain improvements in that class of switching apparatus of which the device shown and claimed in our United States Letters Patent No. 598,705, 20 dated February 8, 1898, is a type; and the object of the invention is to provide an apparatus of this character of a simple and inexpensive nature which shall be readily adapted for attachment to cars already in use, the device being capable of adjustment, so as to accommodate it for use under varying conditions, such as will be found in cars of different constructions.

The invention consists in certain novel features of the construction, combination, and arrangement of the several parts of the improved apparatus, whereby certain important advantages are attained and the apparatus is made simpler, cheaper, and otherwise better adapted and more convenient for use, all 35 as will be hereinafter fully set forth.

The novel features of the invention will be carefully defined in the claims.

In order that our improvements may be 40 the better understood, we have shown in the accompanying drawings an apparatus constructed according to our invention, in which drawings—

Figure 1 is a side elevation showing portions 45 of a car provided with an apparatus constructed according to our invention. Fig. 2, is a view showing part of the under side of the car, together with the mechanism beneath the same. Fig. 3 is an enlarged plan view showing 50 the controlling devices carried on the dashboard. Fig. 4 is an enlarged fragmentary view showing the adjusting devices at

the end of the shaft whereon the switch-actuating levers are mounted, and Fig. 5 is an enlarged fragmentary view showing the adjustable connection between the operating-staff on the car-platform and the levers beneath the car. 55

In the drawings, 1 indicates the body of the car; 2, the platform, having a dashboard 3, 60 and 4 the truck-frame on which the car is supported.

5 5 indicate L-shaped or angular brackets, each bolted at one end to one side of the truck-frame 4, so as to extend beyond the end of 65 the same and in the same plane with each other under the car, the depending ends or vertical arms 6 6 of said brackets being alined and thickened. In the arm 6 of each bracket is formed a vertical slot 7, adapted to 70 receive the end 8 of a transverse shaft 9, which extends across the space between the brackets beneath the car and serves to support the switch-actuating levers 10, which are similar in construction and arrangement to the devices shown in our above-mentioned patent. 75 Each lever 10 is actuated by a lever 11, pivoted, as shown at 12, under the car, its forward end extending under the platform 2 and being coupled to a link 13, the end of which is pivotally connected, by means of a screw 14, (see Fig. 5,) to a slide 15, mounted on a crank-arm 16, secured on the lower end of a staff 17, which extends up above the platform 2, adjacent to the dashboard 3, being journaled 85 at its upper end in a bracket 18, secured to the dashboard.

The slide 15 is adjustably held to the crank-arm 16 by means of the screw 14, by which said slide is coupled to the link 13, said screw acting as a set-screw, and in this way it will be seen a simple and effective coupling for the forward end of the lever 11 and the crank-arm of the staff 17 is provided, permitting these parts to be readily coupled without requiring an accurate adjustment of the pivot-point of said lever 11. 90

There is a staff 17 provided for each of the levers 11, so that the lever 10 at each side of the car may be conveniently and independently actuated to switch the car in either direction from the track along which it is moving, the operation being similar to the operation of the apparatus described and claimed 95 100

in our before-mentioned patent, and the bracket 18 serves as a bearing for each of the said staves, these being adjacent to each other at the central part of the dashboard.

5 Each staff 17 is provided with a crank-handle 19, fixed to it beneath the bracket 18 and projecting away from the dashboard, and on the upper face of each handle 19 is mounted a horizontal pin 20, arranged for endwise movement and adapted to engage one of a series of openings 21 in a curved flange 22, formed at the front face of the bracket 18 at that side thereof, so that when the staff 17 is turned to set the lever 10 at one side of the 15 car the pin 20 by engagement with one of said openings 21 will hold the staff in place. The construction of these parts will be clearly seen from Fig. 3.

The pin 20 is provided with a handle 23, 20 extending up alongside the crank-handle, and said handles 23 and 19 are flattened on adjacent faces to permit them to be pressed closely together by the hand of the operator. The pin 20 is held and guided by a lug 24 on 25 the crank-handle, and on the pin, between the handle 23 and the crank-handle, is arranged a spiral spring 25, which serves to hold the pin normally in engagement with the opening 21 in flange 22. When the handles 30 are pressed together by the hand of the operator, the pin will be disengaged from the opening 21, and when the handles are released said pin will immediately spring back into engagement with the opening.

35 The ends 8 of the shaft 9 are flattened at opposite sides, (see Figs. 1 and 4,) so as to permit of a certain degree of sliding movement along the slots 7 in brackets 5, the shaft being thereby held against turning movement, and in order to permit of adjusting the 40 shaft up or down to set the levers 10, carried on it in proper working position to accommodate differences of height of the brackets above the tracks, as well as to compensate 45 for wear of the parts, we provide adjusting-screws 26 26', arranged in the vertical portions or arms 6 of the brackets at the upper and lower ends of the slots 7, said screws being arranged to bear above and below the 50 ends of the shaft 9.

From the above description of our improvements it will be seen that the apparatus constructed according to our invention is of an extremely simple and inexpensive nature and 55 is especially well adapted for use, since the apparatus is adapted for application to cars already in use, and it will also be seen that the apparatus is capable of some modification without material departure from the 60 principles and spirit of the invention, and for this reason we do not wish to be understood as limiting ourselves to the precise form and arrangement of the parts herein set forth.

Having thus described our invention, what 65 we claim as new, and desire to secure by Letters Patent, is—

1. A switch-actuating apparatus compris-

ing in combination a switch-actuating lever adapted for engagement with the switch-point to be moved, an operating-lever pivotally mounted under the car with one end coupled to the switch-actuating lever and arranged, when moved pivotally, to move said actuating-lever laterally into and out of position to engage the cam or projection on the track, a 75 staff extending above the platform and having below the platform a crank-arm coupled to said operating-lever and arranged to move the same when the staff is turned, a bracket wherein the upper end of the staff is held, a 80 crank-handle on the staff, and a locking device carried by the crank-handle and adapted for engagement with the bracket to hold the staff against turning, substantially as set forth. 85

2. A switch-actuating apparatus comprising in combination a switch-actuating lever adapted for engagement with the switch-point to be moved, an operating-lever pivotally mounted under the car and arranged when 90 moved pivotally, to move the switch-actuating lever into and out of position to engage the cam or projection on the track, a staff extending above the platform and having a crank-arm below the same, a bracket wherein 95 the upper end of the staff is held, a crank-handle on the staff, a locking device carried by the crank-handle and adapted for engagement with the bracket to hold the staff against turning, and an adjustable connection between the crank-arm on the staff and the operating-lever beneath the car, substantially as set forth.

3. A switch-actuating apparatus comprising in combination a switch-actuating lever 105 adapted for engagement with the switch-point to be moved, an operating-lever pivotally mounted under the car with one end coupled to the switch-actuating lever and arranged, when moved pivotally, to move said actuating-lever laterally into and out of position to engage the cam or projection on the track, a staff extending above the platform and having below the platform a crank-arm, a slide mounted for movement endwise along said 110 crank-arm, a set-screw for holding said slide in adjusted position, said set-screw also forming a pivot-point for the connection of said link with the crank-arm, a bracket wherein 115 the upper end of the staff is held, a crank-handle on the staff, and a locking device carried by the crank-handle and adapted for engagement with the bracket to hold the staff against turning, substantially as set forth. 120

4. A switch-actuating apparatus comprising in combination a switch-actuating lever adapted for engagement with the switch-point to be moved, an operating-lever pivotally mounted under the car with one end coupled to the switch-actuating lever and arranged, 125 when moved pivotally, to move said actuating-lever laterally into and out of position to engage the cam or projection on the track, a staff extending above the platform and hav-

ing below the platform a crank-arm coupled to said operating-lever and arranged to move the same when the staff is turned, a bracket wherein the upper end of the staff is held, a 5 crank-handle on the staff, a pin arranged lengthwise on said crank-handle and provided with a handle, a spring for operating said pin, and an apertured flange on the bracket adapted to be engaged by said pin to 10 hold the staff against turning, substantially as set forth.

5. In a switch-actuating device, the combination of brackets secured to and projecting from the truck-frame and having depending 15 ends provided with vertical slots, a shaft hav-

ing its ends formed with flattened sides to fit in and slide along said slots, a switch-actuating lever mounted on said shaft and provided with operating mechanism, and adjusting-screws mounted in the depending ends of said 20 brackets and arranged to bear above and below the ends of the shaft to hold the same in position, substantially as set forth.

In testimony whereof we affix our signatures in presence of two witnesses.

JOHN G. GROSHEIM.
GEORGE L. SEAMAN.
